T. AVELING.
Road-Engine.

No. 228,588.

Patented June 8, 1880.

UNITED STATES PATENT OFFICE.

THOMAS AVELING, OF ROCHESTER, ENGLAND.

ROAD-ENGINE.

SPECIFICATION forming part of Letters Patent No. 228,588, dated June 8, 1880.

Application filed January 13, 1880. Patented in England January 15, 1878.

To all whom it may concern:

Be it known that I, THOMAS AVELING, of Rochester, in the county of Kent, England, have invented an Improved Road Locomotive-Engine, of which the following is a specification.

The object of my invention is to enable road locomotive-engines of six-horse power and upward to be used on railways the usual gage of which is less than the gage required for the road-wheels of engines of such capacity.

Hitherto it has been the practice to place the driving-gear (or the greater portion thereof) between the boiler and the driving-wheels, which necessitated a great width of gage. To provide for a narrower gage without altering the dimensions of the boiler I propose to rearrange the gearing for working with two speeds, and also to place the gearing within the width of the boiler, and also to key all of the gear-wheels firmly on their shafts, and thereby to avoid the inconvenience arising from the use of pinions sliding on feathers.

In the accompanying drawings, Figure 1 is a plan of my improved road locomotive-engine. Fig. 2 is a sectional side elevation of the same, the section being taken on line $x\ x$ of Fig. 1. Fig. 3 is a rear-end elevation of the engine. Fig. 4 is a detail of the gearing, showing the arrangements for changing the speed; and Fig. 5 is a section of Fig. 4, taken on line $x'\ x'$.

Similar letters of reference indicate corresponding parts.

Referring to the drawings, A is the boiler, and B B' are the horn-plates, extending up from the sides of the fire-box above the top of the boiler. Said horn-plates furnish the bearings for the shafting which carries the gearing. In horn-plates B B', above the boiler and to the front, is journaled a crank-shaft, C, with the crank a whereof the connecting-rod D of the engine E is connected. On shaft C, next to the inner side of horn-plate B, are fixed two pinions, $b\ b'$. Back of crank-shaft C a shaft, c , is fixed horizontally in the horn-plates B B', and parallel to the crank-shaft. On fixed shaft c is placed a hollow or sleeve shaft, F, which is adapted to rotate on shaft c , and also, by being made somewhat shorter than the space between horn-

plates B B', it is adapted to receive a laterally-shifting movement.

The sleeve-shaft F is shifted by a lever, G, engaging a horizontally-sliding rod, d , which has a right-angular downward projection, e , provided on its lower end with a fork, f , which fits into an annular groove, g , in sleeve-shaft F.

On the end of shaft F next to horn-plate B is fixed a spur-wheel, h , and outside of the spur-wheel is a pinion, h' . Spur-wheel h can be shifted to engage either one of the pinions $b\ b'$ on shaft C by the movement of shaft F. Pinion h' , by the same movement, is shifted to engage or disengage spur-wheel i , fixed to shaft H, which is journaled in horn-plates B B' just back of boiler A.

On the end of shaft F next to the horn-plate B' is fixed a second pinion, j , in position to be shifted by the movement of sleeve-shaft F in and out of engagement with a second spur-wheel, j' , on shaft H. Shaft H has its end k projecting through its bearing in horn-plate B', and on this projecting end is fixed a pinion, l , which meshes with spur-wheel m , fixed to shaft I, journaled in the horn-plates B B', and carrying in its projecting ends driving-wheels J J.

By reference to the drawings, and from the foregoing description, it will be seen that all the gearing, except pinion l and spur-wheel m , is situated between the horn-plates B B'; consequently it does not extend beyond the width of the boiler and fire-box. This arrangement permits me to restrict the gage of the driving-wheels J J to the ordinary gage of a railway-track. Thereby I am enabled, when I desire, to change the road locomotive-engine to a track locomotive-engine by simply removing the flat driving-wheels J and front wheels, K, and substituting for them the flanged wheels L. (Shown in dotted lines in Fig. 1.)

By means of the laterally-shifting shaft F the speed of the locomotive-engine can be changed and the driving-wheels can be thrown out of gear with the engine in the following manner: By moving lever G to the left spur-wheel h is thrown into gear with pinion b' on shaft C, to which motion is given by the engine D, and by the same movement of shaft F the pinion h' is thrown into gear with spur-wheel i on shaft H. The same movement

throws pinion j out of line with spur-wheel j' on shaft H. This adjustment of the gears causes the motion of the engine to be transmitted, through pinion b' , spur-wheel h , pinion 5 h' , spur-wheel i' , and pinions l and spur-wheel m , to the counter-shaft I and driving-wheels J.

To decrease the speed, lever G is moved to the left, so as to throw spur-wheel h in gear with pinion b , and by this movement pinion 10 h' is thrown out of gear with spur-wheel i , and pinion j' , which is smaller than pinion h' on the same shaft, is thrown into gear with spur-wheel j , which is larger than spur-wheel i , so that the motion transmitted through the gearing 15 b , h , j , and j' is slower than that transmitted through the adjustment first described.

To throw the driving-wheels out of gear with the engine the lever G is moved so as to throw spur-wheel h between pinions b b' .

20 Having thus described my invention, I claim as new and desire to secure by Letters Patent—

1. As an improvement in road locomotive-engines, in combination with the engine E, 25 driving-shaft I, spur-wheel m on shaft I, and pinion l , meshing with the spur-wheel m , the train of gearing arranged, as hereinbefore de-

scribed, between horn-plates B B', for the purpose of transmitting the power from the engine E to driving-shaft I, substantially as 30 specified.

2. The pinions b b' , in combination with the shifting spur-wheel h , shifting pinions h' j , and spur-wheels i j' , as and for the purpose substantially as described. 35

3. The lever G and rod d , provided with the forks f , in combination with the shaft F, substantially as described.

4. The sleeve-shaft F, held on fixed shaft c , in combination with the spur-wheels h and 40 pinions h' j , substantially as described.

5. The horn-plates B B', in combination with shaft C, carrying pinions b b' , fixed shaft c , and sliding shaft F, carrying spur-wheel h and fixed pinions h' j , shaft H, carrying spur-wheels i j and pinion l , and shaft I, carrying spur-wheel m and driving-wheels J J, as and for the purpose substantially as described. 45

THOMAS AVELING.
